UNITED STATES PATENT OFFICE.

CANUTE H. FORSBERG AND CARL W. FORSBERG, OF PATTON, PENNSYLVANIA.

SCRAPER ATTACHMENT FOR VARIOUS BRUSHES.

Application filed March 6, 1922. Serial No. 541,556.

To all whom it may concern:

Be it known that we, CANUTE H. FORSBERG and CARL W. FORSBERG, citizens of the United States, residing at Patton, in the 5 county of Cambria and State of Pennsylvania, have invented certain new and useful Improvements in Scraper Attachments for Various Brushes, of which the following is a specification, reference being had to the 10 accompanying drawings.

It is the purpose of the present invention to provide an improved knife or scraper, for attachment to various brushes, such as scrub brushes, stove brushes, paper hanger 15 brushes and paint brushes and the like, for the removal of dirt and other foreign matter, before scrubbing, or polishing stoves, or before hanging paper, and before painting or otherwise decorating surfaces.

20 Very often when scrubbing, painting or performing work of a similar character, it is necessary to remove some foreign matter, dirt or the like that would if left would not present a neat appearance.

25 Therefore the present invention further aims to provide an improved knife or scraper applicable to the handle of any kind of brush, and the blade of which can be easily and conveniently opened at any time, for 30 the purpose of removing dirt and other foreign matter.

Still another purpose is the provision of 35 a knife or scraper attachment of this character comprising a folded metal piece comprising opposed walls secured to the wood portion of the brush, together with a blade or knife pivoted between the walls of the folded metal strip, said blade being provided with means, such as a roll on the rear 40 edge of the blade, so that its end may engage a notch of one of the sides or walls of the folded metal strip, in order to limit the blade in its open position.

A still further purpose is the provision of 45 a roll on the rear edge of the blade, between which and the blade the edge of the notch of one wall of the holder for said blade engages, for the purpose of limiting the blade in its open position, and thereby acting to 50 relieve the lateral strain upon the pivot of the blade.

It is to be understood that the particulars herein given are in no way limitative and that while still keeping within the scope of 55 the invention, any desired modifications of

detail and desired proportions may be made in the apparatus according to circumstances.

The invention comprises further features and combination of parts, as will be herein-after set forth, shown in the drawings and 60 claimed.

In the drawings:—

Figure 1 is a view of the improved knife or scraper attachment as applied to the 65 wood portion of the brush;

Figure 2 is a longitudinal sectional view through the same on line 2—2 of Figure 1;

Figure 3 is a view showing the knife or scraper as applied to the handle of another 70 form of brush;

Figure 4 is an enlarged detail perspective view of the pivotal connection between the blade and the opposite sides of the metal strip, between which the blade is pivoted, showing the roll which cooperates with the 75 notch in one wall of the metal holder for the blade;

Figure 5 is a cross sectional view on line 5—5 of Figure 4.

Referring to the drawings, 1 designates 80 the handle of a brush, whether it be a scrub brush, paint brush, stove polishing brush, or a paper hanger's brush, or any other form of brush, and attached to the handle is a folded strip of metal 2. This strip of metal 85 is folded upon itself as at 3, and between the plies of the folded piece, adjacent the bight thereof is a metal filler 4. Passing through the plies of the metal strip and through the filler, and secured in the wood portion or 90 handle of the brush are screws 5, which secure the folded metal strip to the handle. Pivoted between the sides of the folded metal strip as at 6 is a knife or blade 7. This blade or knife may be any suitable 95 shape, or proportions, preferably short and broad as illustrated, and is provided with sharp scraping edges 8 and 9, for the purpose of removing dirt and other foreign matter from a surface which is to be scrubbed, painted or otherwise covered.

100 The rear edge of the blade or knife has an extension 10, which is rolled upon itself, and projects laterally from the blade. This roll may be any suitable length, preferably as 105 shown, and where one end of the wall of the roll projects or turns toward the body of the blade, the edge 11 of a notch 12 of one of the sides of the metal strip engages. One edge of the notch is curved as shown at 13, constitut- 110

ing a cam, over which the edge portion of one end of the roll operates, so that one edge of the end of the roll may engage the shoulder 14 of the notch, thereby limiting the blade or 5 knife in its open position. Before the end of the roll engages the shoulder of the notch, it is necessary to force the roll over the curved cam edge of the notch. In fact due to the extension being turned upon itself to 10 form the roll, and since the end of the extension which forms the roll is not attached to the body of the knife, there is a certain degree of resiliency of the terminal of the extension forming the roll, therefore the 15 roll will act to cam over the curved edge of the notch, in order to permit the edge of the end of the roll to contact with the shoulder of the notch, and hence limit the blade or knife in its open position.

20 From the foregoing it will be seen that there has been devised a simple, efficient and practical scraper or knife to be used in connection with brushes of the various characters herein named, for the purpose of effectively removing the dirt or other foreign matter from a surface which is to be painted, papered or otherwise covered.

The pivoted end of the blade 7 is provided with a depression 15, and one of the 30 sides of the piece or strip of metal 2 is also provided with a depression 16. This depression 16 causes a bulge to form on the inner face of the side of said strip of metal, adapted to engage the depression 15 when 35 the blade or knife is open, thereby assisting materially in holding the knife in an open position.

It will be noted that since the roll or extension 10, where it engages the edges 11 and 40 13, is more or less resilient, and since this resilient portion bears upon one side of the sheet metal strip, the bulge caused by the depression 16 will engage the depression 15, assisting materially in holding the blade in 45 an open position, and securely latched in such position. In fact the roll or extension

10 where it engages the notch 12 has an action of bearing down upon one side of the sheet metal strip or strap, and acts to draw the two pieces together, to insure holding 50 the bulge in engagement with said extension.

The invention having been set forth, what is claimed is:—

1. In a scraper attachment, a folded strip of metal adapted to be mounted on a body, 55 means for spacing the plies of the strip, a scraping blade pivoted between the plies, one end of one of the plies having a notch, and a roll extending longitudinally along the back edge of the blade and having a yieldable portion to engage the shouldered end 60 of the notch to limit the blade in its open position.

2. The combination with a body, of a metal strip folded upon itself and secured 65 to said body, the end of one ply of the metal strip having a notch provided with a shoulder, a blade pivoted between the plies of said metal strip, said notch having a cam edge, and a roll carried by the rear edge of 70 the blade and having a yieldable portion to cooperate with the cam edge when opening the blade, whereby the end of said yieldable portion of the roll may contact with the notch and limit the blade in its open position. 75

3. The combination of a scraper adapted to be mounted on a body, comprising a holder to be secured to said body, said holder comprising opposite plies, the edge of one 80 end of one ply having a notch, a blade pivoted between the plies of said holder and having a roll at one edge provided with a spring extension, adapted to cam over one edge of said notch, whereby it may engage 85 the shoulder of the notch to limit the blade in its open position.

In testimony whereof we hereunto affix our signatures.

CANUTE H. FORSBERG.
CARL W. FORSBERG.
